Isaac Townsend of Philadelphia Penna.
Letters Patent No. 2078-Dated May 30 1865.
Design for a Lemon Press.

The schedule referred to in these letters patent and making part of the same.

To all whom it may concern:

Be it known that I, Isaac Townsend of the City of Philadelphia, in the State of Pennsylvania, have originated or produced a new Design for a Lemon Press; of which the following is a full, clear and exact description, reference being had to the accompanying drawings, making part of this specification, in which figure 1 is a perspective view of the said press opened; and figure 2 a central, vertical, longitudinal section of the same closed; like letters of reference indicating the same parts when in both figures.

The nature of my said design consists in having the curved disk and the levers which together constitute one of the two parts of the press, each of a single piece in the form herein after described and set forth.

In the drawings A and A' are the levers, and a² a³ the disks. The levers A are each of an open elliptic form between their handles and their common connecting joint; and the curved disks a² a³ are cast simultaneously with the levers, so as to be fastened by two opposite edges in the middle of the open space of its respective lever, as shown in figure 1 and so that, when the said levers are closed together, the convex side of the disk a³ will be concentric with the concave side of the disk a² and at the same time leave a space of about an eighth of an inch, more or less, between them, as shown in figure 2.

Having thus described my invention or production, what I claim as new and desire to secure by Letters Patent is

The design for a Lemon Press herein set forth.

Witnesses:

Benj. Morrison,
V.R. M. C. Willmarth,

Isaac Townsend.
